6 Claims. (Cl. 67—33)

This invention relates to a flash-light apparatus for use as a signalling device or for the temporary illumination of objects for photographic or other purposes, and consists broadly in the provision of a cylinder which may be connected like a gun barrel to a rifle butt or to a pistol handle and which is closed at the free end by a grate against which a flash-light cartridge can be held and ignited by means of a spring pressed plunger released by means of a trigger, the cartridges being fed through a lateral port in the cylinder from an annular magazine which is rotatable about the cylinder and which is rotated by the feeding mechanism.

Figs. 1—4 of the accompanying drawings represent sectional side views of an apparatus according to the invention showing the firing mechanism in different operative positions.

Fig. 5 is a cross-section on the line V—V of Fig. 4,

Figs. 6—9 are sectional, fragmentary side views showing the loading mechanism in different operative positions.

Figs. 10—13 are cross-sections on the lines X—X to XII—XII of Figs. 6—9 respectively.

Fig. 14 is a view of the apparatus as connected to a pistol handle, and

Fig. 15 is a view of the apparatus as connected to a rifle butt.

The apparatus comprises a cylinder 1 which may be connected either to a pistol handle 2 as shown in Fig. 14, or to a rifle butt 32 as shown in Fig. 15. The free end of the cylinder is closed by a grate 16 one bar of which carries an inwardly projecting firing pin 17. Mounted rotatably on the cylinder is an annular cartridge magazine 11 which is divided by means of partitions 26 into chambers adapted to receive flash-light cartridges. The chambers are open towards the

centre of the magazine, and the cartridges are retained in all except the top chamber by means of a segmental shell 33 connected to a rigid wall 14 over the edge of which a flange 35 on the magazine engages, as shown in Fig. 4. A spring pressed ball 15, housed in a socket on the wall

14, is adapted to snap into recesses 28 in the adjacent wall 13 of the magazine for retaining the latter with any one of the cartridge chambers in the top position. In this position of a cartridge

chamber, the enclosed cartridge drops through the shell 33 and through a lateral port 34 in the cylinder 1 into the latter. A sleeve 9, which is displaceable inside the cylinder 1, normally closes the port 34 and is fitted with a finger piece 10 whereby it can be displaced for opening the

port. The finger piece projects through a slot 30 in the cylinder 1 and is adapted to engage in longitudinal slots 29 made in a sleeve 31 which is mounted on the cylinder 1 and which is connected to the wall 12 of the magazine 11 so as to rotate together with the latter. The slots 29 in the sleeve 31 are narrow and open-ended for admitting the finger piece 10, there being one slot for each cartridge chamber in the magazine. The slot 30 in the cylinder 1 is triangular in that it is provided with rearwardly diverging edges, one being parallel to the cylinder axis and the other helical. The finger piece 10, on being used for displacing the sleeve 9 so as to open the port 34, is made to follow the helical edge of the slot 30, and it will then, owing to its engagement with the sleeve 31, turn the magazine 11 from one feeding position into the next. In the illustrated arrangement there are six cartridge chambers, and the slot 30 is adapted to effect, at each displacement of the sleeve 9, a rotary displacement of the magazine through 60°. At the end of the rearward movement, the finger piece 10 leaves the slot 29 in the sleeve 31, and the finger piece, still following the edge of the slot 30, can then be turned and moved into the next slot 29 of the sleeve.

The cylinder 1 contains a hollow plunger 3 which is guided, partly in the sleeve 9 and partly on a bolt 4 secured to the rear end of the cylinder. A spring 5 in the plunger bears at one end against the closed end of the plunger and at the other end against the bolt 4 and urges the plunger in a forward direction for pressing an admitted cartridge against the grate 16. A finger piece 6, which engages the plunger through a longitudinal slot in the cylinder, is used for retracting the plunger and limits the movements of the latter by abutment against stops 7 and 8. In the retracted position of the plunger the latter is retained by a pivoted catch 20 which for this purpose snaps into engagement with a notch 19 in the plunger. The catch is connected by means of a link 21 to a trigger 23 by means of which it can be actuated for releasing the plunger, the plunger being controlled by a spring 22, being controlled by a spring 22.

Each cartridge is provided with a fulminate and is adapted to be ignited by the impact of this fulminate with the firing pin 17.

To operate the apparatus, the plunger 3 is first retracted by means of a finger piece 6 into the position shown in Fig. 1, it being retained in this position by the catch 20. Thereupon the finger piece 10 is moved from the position shown

in Figs. 6 and 10 into the position shown in Figs. 7 and 11, so that the port 34 will be opened and so that the magazine will be rotated for dropping a cartridge 24 through the gap 21 in the shell 33 into the cylinder 1. The finger piece 10 is finally moved into position opposite a fresh slot 29 in the sleeve 31, as shown in Figs. 8 and 12, and pushed home through said slot, as shown in Figs. 9 and 13. The admitted cartridge will then be pushed forwards by the sleeve 31 into the position shown in Figs. 2 and 9 whereupon the apparatus is ready for firing. The plunger 3, on being released by means of the trigger 23, springs forwards and forces the admitted cartridge 15 against the grate 16, and the cartridge will be ignited by impact with the firing pin 17. Fig. 3 shows the burning cartridge 25, and Fig. 4 shows how the cartridge is maintained by the plunger in contact with the grate during its consumption 20 and diminution.

The reflector 18 may be mounted on the cylinder 1 so as to have the flame projected by the burning cartridge more or less in its focus according to requirements.

25 We claim:

1. A flash-light apparatus comprising a cylinder having a lateral port, a grate structure closing one end of said cylinder, an annular magazine for flash-light cartridges adapted to revolve about said cylinder over said port, means for feeding cartridges from the magazine through the port into the cylinder, a spring-controlled plunger in said cylinder adapted to project admitted cartridges against said grate, means for 30 retracting the plunger from the grate in opposition to the spring pressure, means for retaining the plunger in retracted position, means for releasing the plunger, and means operated by the impact of the plunger, for igniting the cartridge 35 behind the grate.

2. A structure as claimed in claim 1 wherein the means for feeding cartridges into the cylinder comprises a sleeve arranged outside the cylinder and connected to the magazine, a sleeve arranged within the cylinder between the latter and the plunger and adapted to be displaced for opening and shutting the port of the cylinder, and a finger piece connected to said latter sleeve for the displacement of the latter and projecting through a slot in the cylinder and adapted to 10 engage in slots in the first mentioned sleeve, the slots in the latter being narrow and open-ended for admitting the finger piece, and the slot in the cylinder being triangular and arranged so that the finger piece will, by following the edges 15 of the triangular slot, displace the inner sleeve for opening the port, turn the magazine for discharging a cartridge through the port, and then enter a fresh slot in the sleeve.

3. A structure as claimed in claim 1 wherein the means for retaining the plunger in retracted position consists of a pivoted catch adapted to engage in a notch in the plunger, and wherein the means for releasing the plunger consists of a trigger in operative connection with said catch.

4. A structure as claimed in claim 1 wherein the means for igniting the cartridges consists of a firing pin carried by the grate and adapted to co-operate with a fulminate in each cartridge.

5. The structure claimed in claim 1 in combination with a rifle butt secured to the cylinder.

6. The structure claimed in claim 1 in combination with a pistol handle secured to the cylinder.
